(57) **CLAIM**

The ornamental design for a construction toy component, as
shown and described.

DESCRIPTION

FIG. 1 is an end elevation view of the construction toy com-
ponent, the other end being identical;

FIG. 2 is a top perspective view of the construction toy com-
ponent of FIG. 1;

FIG. 3 is a side elevation view of the construction toy com-
ponent of FIG. 1, the other side being identical; and,

FIG. 4 is a top plan view of the construction toy component of
FIG. 1.

The bottom forms no part of the claimed design.
